(57) **CLAIM**

The ornamental design for a vaporizer substantially as
shown and described.

DESCRIPTION

FIG. 1 is a top perspective view of the vaporizer;
FIG. 2 is a bottom perspective view of the vaporizer;
FIG. 3 is a top view of the vaporizer;
FIG. 4 is a bottom view of the vaporizer;
FIG. 5 is a left side view of the vaporizer;
FIG. 6 is a right side view of the vaporizer;
FIG. 7 is a front view of the vaporizer;
FIG. 8 is a rear view of the vaporizer;
FIG. 9 is an exploded top perspective view of the vaporizer
in the open position;
FIG. 10 is an exploded bottom perspective view of the
vaporizer in the open position;
FIG. 11 is a top view of the vaporizer in the open position;
FIG. 12 is a bottom view of the vaporizer in the open
position;
FIG. 13 is a left side view of the vaporizer in the open
position;
FIG. 14 is a right side view of the vaporizer in the open
position;
FIG. 15 is a front view of the vaporizer in the open position;
and,
FIG. 16 is a rear view of the vaporizer in the open position.
The evenly spaced broken lines in the drawings depict
portions of the vaporizer that form no part of the claimed
design.
